CLAIM

The ornamental design for a table, as shown and described.

DESCRIPTION

1. Table

FIG. 1.1 is a perspective view of the design; fig. 1.2 is a left view thereof; fig. 1.3 is a right view thereof; fig. 1.4 is a front view thereof; fig. 1.5 is a rear view thereof; fig. 1.6 is a top view thereof; fig. 1.7 is a bottom view thereof.

Those portions of the table shown in fig. 1.7 in broken line form no part of the claimed design.
